CONTAINER CAP

David Donaldson, Wilmington, Del., assignor to Container Corporation of America, Chicago, Ill.

Filed Apr. 9, 1969, Ser. No. 16,643

Term of patent 14 years

Int. Cl. D9—02

U.S. Cl. D9—284

FIG. 2

FIG. 1

FIG. 3

FIG. 4

FIG. 1 is a side elevational view of a container cap, showing my new design;

FIG. 2 is a sectional view taken generally along the line 2—2 of FIG. 1;

FIG. 3 is a bottom plan view of a container cap shown in FIG. 1; and

FIG. 4 is a top plan view thereof.

I claim:

The ornamental design for a container cap, as shown.
